CLAIM

The ornamental design for a flip-top loose tool bit container, as shown and described.

DESCRIPTION

FIG. 1 is a front perspective view of a flip-top loose tool bit container of the present invention;

FIG. 2 is a front view thereof;

FIG. 3 is a rear view thereof;

FIG. 4 is a left-side view thereof, which is similar to a right-side view thereof;

FIG. 5 is a top view thereof; and,

FIG. 6 is a bottom view thereof.

The ornamental design which is claimed is shown in solid lines in the drawings. Any broken lines in the drawings are for illustrative purposes only and form no part of the claimed design.
